Primary Examiner — Leah Macchiarolo*Assistant Examiner* — Christina Gabrielle Cosden*(74) Attorney, Agent, or Firm* — Buchanan Ingersoll & Rooney PC(57) **CLAIM**

The ornamental design for a latch actuator, as shown and described.

DESCRIPTION

FIG. 1 is an isometric view of a latch actuator, as viewed from the top, front and right sides, and according to an exemplary embodiment of the present invention;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof; and,

FIG. 7 is a bottom plan view thereof.

The broken lines showing of features of the latch actuator form no part of the claimed design.

1 Claim, 6 Drawing Sheets(56)
